PANEL FOR A FURNITURE DRAWER OR THE LIKE

Melbourne F. Smith, Lenoir, N.C., assignor to Broyhill
Furniture Factories, Lenoir, N.C., a partnership

Filed Oct. 12, 1962, Ser. No. 72,092

Term of patent 14 years

(Cl. D33—1)

FIGURE 1 is a front elevational view of my new design for a panel for a furniture drawer or the like; and FIGURE 2 is a top plan view thereof.

The back of the panel for a furniture drawer or the like is conventionally plain.

I claim:

The ornamental design for a panel for a furniture drawer or the like, as shown and described.
